UNITED STATES PATENT OFFICE.

RAYMOND F. BACON AND BENJAMIN T. BROOKS, OF PITTSBURGH PENNSYLVANIA, AND CLINTON W. CLARK, OF CHICAGO, ILLINOIS, ASSIGNEES TO GULF REFINING COMPANY, OF PITTSBURGH, PENNSYLVANIA, A CORPORATION OF TEXAS.

APPARATUS FOR THE MANUFACTURE OF GASOLENE.

1,334,731.

Specification of Letters Patent. Patented Mar. 23, 1920.

Original application filed May 2, 1913, Serial No. 764,982. Divided and this application filed February 1, 1915. Serial No. 5,428.

To all whom it may concern:

Be it known that we, RAYMOND F. BACON, BENJAMIN T. BROOKS, and CLINTON W. CLARK, all citizens of the United States, residing, respectively, at Pittsburgh, Allegheny county, State of Pennsylvania, and Chicago, county of Cook, State of Illinois, have invented certain new and useful Improvements in Apparatus for the Manufacture of Gasolene; and we do hereby declare the following to be a full, clear, and exact description of the invention, such as will enable others skilled in the art to which it appertains to make and use the same.

In our Patent No. 1,131,304, we have described the treatment of mineral oils whose boiling point is 250° C. and upward, for the production therefrom of a mixture of hydrocarbons principally of the C_nH_{2n+2} series, boiling below 200° C. said product being intended particularly for use as a fuel for internal combustion engines.

The present application constitutes a division of the application of the patent above referred to, and relates particularly to apparatus for carrying into effect the method described in said patent.

Referring to the accompanying drawing,—

Figure 1 represents partly in section, and partly in elevation, one form of such apparatus embodying the invention;

Fig. 2 represents a partial view of a modification thereof, applicable to multiple units.

Similar letters of reference indicate similar parts in both views.

Referring particularly to Fig. 1, A indicates a storage tank for the petroleum hydrocarbons to be treated and B indicates a pump for delivering a regulated supply therefrom to the still through the conduit a.

In Fig. 1, is shown a single unit consisting of a tube b, of steel or other suitable metal, whose length is preferably 20 ft. or more, when the internal diameter of the tube is 6 inches. The heating zone of the tube is intermediate of its ends, and, in the form shown in Fig. 1, consists of a fire brick chamber C having suitable air inlets, as d, and a suitable exit opening, as e, for the products of combustion. The chamber C may receive its heat from any convenient

source, as, for instance, a series of annular gas burners f, supplied with gas from the gas conduit D whose branches g terminate in injecting tips, as shown, which draw in a suitable supply of air through the bells h, opening into the atmosphere. At its lower end, the tube b communicates with a tar and coke receiving receptacle E located below outside of the heating zone.

As explained in our patent hereinbefore referred to, while the production of the desired product depends upon the maintenance of the high temperature and high pressure hereinafter described, the rate of production is a function of the area of heating surface employed and, for most purposes, may be regarded as represented by the ratio of the heating surface to the volume of the oil within the heating space. Accordingly, it is found that the maximum yields, in a given unit of time from a given volume of oil heated, are obtained when the ratio of the heating surface to the volume is correspondingly large. In practice, we have employed with entirely satisfactory results tubes of an internal diameter as large as 19 inches, (corresponding to a ratio, expressed in comparable units, of internal periphery to internal capacity of 1:4.7; this numerical ratio being derived when the inch is taken as the unit of measurement). We do not recommend the employment of tubes of materially larger diameter because of the rapidly decreasing yield in gasoline beyond that point.

At the beginning of the operation, the charge of oil to be cracked and distilled is established up to the level indicated in Fig. 1, that is to say, at a level slightly higher than the internal wall of the top of the heating chamber C. This level of the body of oil is kept practically constant, by means of the pump B, which supplies oil to the interior of the tube as the cracking and distillation proceed. Accordingly, the products of combustion do not come into direct contact with any portions of the tube not occupied by the liquid oil, and consequently, the danger of destructive decomposition of any portion of the vapors by coming into contact with overheated portions of the tube above the zone of liquid oil is minimized.

and the formation of an adhering layer of coke upon such portion of the walls of the tube is avoided.

The free portion of the tube extends above the furnace setting, as shown, for a distance of say 5 feet. The vapors pass, by means of the pipe *i*, to the condenser coil *j*, contained within the cooling receptacle *K*. The condenser coil is provided at its end with a valve *k* and discharges into the receptacle *G*. The uncondensed gases and vapors from the receptacle *G* pass by the pipe *l* into a body of oil contained within the receptacle *H*, wherein such particles of oil as are contained in the residual gases are trapped and recovered. The surplus gases and vapors pass off through the conduit *m*. At the bottom of the receptacle *E*, a pipe *n* conveys the residual tar and coke to a receiving tank *I*, the flow being under the control of a regulable valve *s*.

The mineral oils to be treated in the apparatus and from which the desired product is to be obtained are petroleum hydrocarbons, as, for instance, American and Mexican petroleums. With the form of apparatus shown in Fig. 1, the receptacle *E* and the tube *B* are filled to the level indicated, and the annular burners *f* are ignited. The temperature then rises to the range of from 350° C.-500° C. and, the pressure is likewise permitted to rise, by shutting off the valve *K* either wholly or partially, as the case may be, until the pressure gage *t* indicates the pressure desired, that is to say, a pressure within the range of 60 pounds to 300 pounds per square inch. Thus, at 100 lbs. pressure, about 80% of the entire body of oil may be distilled with the production of a resultant condensate containing a large percentage of material boiling below 200° C., the temperature being about 425° C. About 35% of the condensate obtained at this pressure and temperature has a boiling point below 150° C. and almost all of this product is of the C_nH_{2n+2} series, appropriate for use for the ordinary purposes of gasoline, as, for instance, for use as fuel for internal combustion engines and would usually be rated commercially as gasoline. In general, it is preferred, as indicated, to operate at a pressure of 100 lbs. for the reason that the relative portion of material boiling below 150° C. is greater when the operation is conducted at 100 lbs. pressure than when conducted at the lower pressure of 60 lbs. per square inch. The higher pressures up to 300 lbs. are employed when it is desired to still further increase the relative proportion of material in the condensate boiling below 150° C. but at the higher pressures there is progressively more coke and gas formed and hence a lower percentage of total condensate is obtained.

During the cracking and distilling operation, any particles of tar and coke that may

be formed in the body of the distilling oil tend to fall through the vertical heating zone, by gravity, into the receiving space of the chamber *E*. A relatively small amount of tar and coke will, in the course of time, 70 build up upon the vertical walls of the tube *B* within the heating zone, but these accumulations are relatively unimportant and slow of formation, and, should they become excessive, may be readily removed by the use 75 of any ordinary boiler flue cleaner, or the like. The tarry petroleum residue containing the fine coke particles accumulating in the receptacle *E* is drawn off from time to time through the pipe *n* into the receiver *I*. 80

In the form of apparatus indicated in Fig. 2, there is shown a series of individual tubes *b*, having at the bottom a common header *E'* corresponding in function and location to the receptacle *E* of Fig. 1. The tubes *b* are 85 located in a heating flue *C'* supplied with a flow of hot products of combustion from any suitable source, so as to heat the tubes to the high temperatures hereinbefore referred to, the header *E'* being located in a cooler space 90 below the heating flue. *a'* indicates a supply pipe communicating with the interior of the several tubes *b*, so as to furnish oil thereto. So also, the pipe *v* constitutes the exit pipe for the vapors. The supply pipe *a'* and the 95 exit pipe *n'* from the header *E'* are connected by the cross-connecting pipe *v* having a valve *x* and containing the liquid level gage *w*, so that the operator will be able to know at any time the oil level within the 100 several tubes *b*. The mode of operation of this modification will be clear from what has been said in regard to the mode of operation of the form of the apparatus shown in Fig. 1, and need not be further elaborated. 105

It is characteristic of our invention that the receptacle in which the oil is contained is provided with an upper cracking and distilling zone, wherein, during the formation of the gasoline product, the incidental particles of tar and coke produced are free to drop by gravity into a lower settling zone whereby cementation of the particles upon the heated surfaces is prevented. In the specific embodiment of the invention illustrated in the drawing, the receptacle for containing the oil is shown as located within an exterior fire chamber or fire tube, but it will, of course, be understood that, without departing from the spirit of the invention, this relative arrangement may be reversed. 115

What we claim is:

1. Apparatus for cracking and distilling petroleum oils under pressure, comprising a 125 receptacle for containing the oil, said receptacle having an upper cracking and distilling zone with an unobstructed interior, and having a lower settling zone, means for externally heating to the desired tempera- 130

- ture the cracking and distilling surfaces with which the oil is in contact, the settling zone of the receptacle being in free communication with the cracking and distilling zone so as to continuously remove by gravity out of the cracking and distilling zone the particles of coke and tar produced therein, means for feeding the oil into the receptacle under the necessary pressure, and 10 means for establishing and maintaining a pressure between sixty and three hundred pounds per square inch within the receptacle during the operation; substantially as described.
- 15 2. Apparatus for cracking and distilling petroleum oils under pressure, comprising a receptacle for containing the oil, means for heating to the desired temperature the cracking and distilling heating surfaces 20 with which the oil is in contact, the ratio (expressed in comparable units) of the cracking and distilling heating surfaces of the receptacle to the volume exposed to said surfaces being not substantially less than 25 1:4.7, (this ratio being derived when the inch is employed as the unit of measurement), means for feeding the oil into the receptacle under the necessary pressure, and means for establishing and maintaining a 30 pressure between sixty and three hundred pounds per square inch within the receptacle during the operation; substantially as described.
- 35 3. Apparatus for cracking and distilling petroleum oils under pressure, comprising a receptacle for containing the oil, said receptacle having an upper cracking and distilling zone with an unobstructed interior, and having a lower settling zone, means for externally heating to the desired temperature the cracking and distilling surfaces with which the oil is in contact, the settling zone of the receptacle being in free communication with the cracking and distilling zone so 40 as to continuously remove by gravity out of the cracking and distilling zone the particles of coke and tar produced therein, and means for establishing and maintaining a pressure between sixty and three hundred 45 pounds per square inch within the receptacle during the operation, a pump for supplying oil to the receptacle so as to maintain a constant level of oil therein, a condenser, a closed receptacle into which the condenser discharges and in which the gases 50 separate from the condensate, and an additional receptacle containing oil through which said gases pass for the recovery of oily particles suspended therein; substantially as described.
- 55 4. Apparatus for cracking and distilling petroleum oils under pressure, comprising a series of upright tubes for receiving the oil to be treated, means for heating said series of tubes to the desired cracking and distilling temperature, means for establishing and maintaining a pressure between sixty and three hundred pounds per square inch within the receptacle during the operation, a common header below the series of tubes for the reception of particles of tar and coke produced in the oil columns contained in the tubes, an oil-supply pipe common to the tubes, a pump for supplying oil to the tubes through said common oil-supply pipe, a cross-connection pipe establishing communication between the oil-supply pipe and the header, and a condenser; substantially as 60 described.
- 65 5. Apparatus for cracking and distilling petroleum oils under pressure, comprising a receptacle having an upper cracking and distilling zone with an unobstructed interior, and having a lower settling zone, means for externally heating to the desired temperature the cracking and distilling surfaces with which the oil is in contact, the settling zone of the receptacle being in free communication with the cracking and distilling zone so 70 as to continuously remove by gravity out of the cracking and distilling zone the particles of coke and tar produced therein, and means for establishing and maintaining a pressure between sixty and three hundred 75 pounds per square inch within the receptacle during the operation, a pump for supplying oil to the receptacle so as to maintain a constant level of oil therein, a condenser, a closed receptacle into which the condenser discharges and in which the gases separate from the condensate, and an additional receptacle containing oil through which said gases pass for the recovery of oily particles suspended therein; substantially as 80 described.
- 85 6. Apparatus for cracking and distilling petroleum oils under pressure, comprising a series of upright tubes for receiving the oil to be treated, means for heating said series of tubes to the desired cracking and distilling temperature, means for establishing and maintaining a pressure between sixty and three hundred pounds per square inch within the receptacle during the operation, a common header below the series of tubes for the reception of particles of tar and coke produced in the oil columns contained in the tubes, an oil-supply pipe common to the tubes, a pump for supplying oil to the tubes through said common oil-supply pipe, a cross-connection pipe establishing communication between the oil-supply pipe and the header, and a condenser; substantially as 90 described.
